POWER JACK FOR PUMPS AND THE LIKE

Ross T. Cruikshank, Minneapolis, Minn., assignor
of one-half to Carl A. Anderson, Minneapolis,
Minn.

Application December 23, 1946, Serial No. 717,840

3 Claims. (Cl. 74—25)

1

This invention relates to improvements in power jacks for longitudinally reciprocating pump plungers or the like by the application of either rotary or oscillatory power.

My present invention is an improvement over the structure disclosed in my application Serial No. 651,359 filed March 1, 1946, entitled "Pump Jack" and which issued as Patent No. 2,445,133 on July 13, 1948.

The structure of my earlier application, while adapted for wide general use, was particularly conceived for use on farms and in the pumping of water and other liquids where the required stroke was comparatively short.

It is an object of my present invention to provide a power jack adapted for very heavy work, such as, for example, the pumping of oil in oil fields, whereby substantial elimination of sharp pulsations and jerkiness is achieved and whereby the cooperating parts of the working mechanism are so related as to give great efficiency, maximum wear, and to adapt a pump to heavy work and efficient operation where strokes in excess of seventy inches are required.

Another object is the provision of improvements over my earliest structure whereby power converting or motion changing gears are related with a driving mechanism, frame, and reciprocating carriage to align the parts for maximum efficiency, provision of adequate bearing surface symmetrically disposed with reference to the line of thrust and pull, and to impart power in both lifting and thrust strokes advantageously.

A still further object is the provision of a commercially practical, heavy-duty pump jack which, through interchangeability of some of the parts and cooperation of working mechanism, can be manufactured at relatively low cost.

These and other objects and advantages of the invention will more fully appear from the following description made in connection with the accompanying drawings, wherein like reference characters refer to the same or similar parts throughout the views and in which:

Figure 1 is a longitudinal vertical sectional view taken substantially on the line 1—1 of Fig. 3;

Figure 2 is a side elevation of the pump jack;

Figure 3 is an end elevation of the pump jack;

Figure 4 is a partial vertical transverse sectional view through the power converting mechanism;

Figure 5 is a horizontal sectional view taken substantially on the line 5—5 of Figure 4;

Figure 6 is a side elevation view of an alterna-

2

tive form of the gear wheel mounting member with the front face of the casing cut away; and

Figure 7 is a vertical sectional view of said alternative form taken substantially on the line 6—6 of Figure 6.

In the form shown, the mechanism of my invention is mounted upon a suitable base 10 anchored to the ground and has a vertically movable element such as a pump or piston rod 11 centrally disposed therein and extending therethrough, said piston rod being mounted for reciprocation in a pump cylinder or well pipe (not shown). A supporting frame is provided which comprises four spaced guiding members such as the rods 12, which are rigidly mounted in opposed relation on said base 10.

Four interchangeable identically similar castings are provided and are mounted on said guide rods 12. Two of said castings are slidably mounted on the lower portion of said guide rods 12 to form reciprocable carriage members 13. The upper extremity of piston rod 11 has an enlarged pin-connecting member 14 fixed thereto. A pin 15 traverses the space between the lower portions of reciprocable carriage members 13 and connects said pin-connecting member 14 therewith being journaled in said carriage members 13. The space between the upper portion of said carriage members 13 being traversed by a stub shaft 16 which is journaled in bearings therein.

The other two interchangeable castings are inverted and firmly connected to the upper portion of said guide rods 12 to form stationary mountings 17, said mountings 17 being aligned with carriage members 13 and mounted on the same guide rods respectively as carriage members 13 in upwardly spaced relation thereto.

Either rotary or oscillatory power may be used to drive the disclosed mechanism; in the form shown rotary power is provided as by sheaves 18 connected with an external source of power and fixed on one end of a pinion shaft 19, said shaft 19 being journaled for rotation in bearings in the upper portion of said stationary mountings 17 and extending therethrough. A pinion gear 20 is fixed on the other end of said shaft 19 and is meshed with a driving bull gear 21. A drive shaft 22 is axially fixed in bull gear 21 and is journaled in bearings in the lower portion of said stationary mountings 17 extending therethrough and being journaled therein.

A power-converting mechanism is provided, 55 which comprises a pair of power-converting gear

wheels 23 and 24 connected by and journaled in a gear wheel mounting member 25. The gear wheel 23 is eccentrically affixed on said drive shaft 22 perpendicularly thereto and medially disposed between the stationary mountings 17. Gear wheel 24 is eccentrically mounted on shaft 16 perpendicular thereto and medially disposed between the carriage members 13. Said gear wheel 24 is of the same diameter as gear wheel 23 and is meshed therewith and the radii of eccentricity of the two gear wheels are equal. In the form shown in Figs. 1 to 5 inclusive, the central peripheral portion has a guide way cut therein adapted to receive the gear wheel mounting member 25. The gear wheel mounting member 25 has two aligned apertures therethrough and is split through the two apertures to form a two-piece construction for assembly purposes in connecting it in said guideways where said member 25 is held in assembled position as by bolts therethrough. The internal peripheries of said mounting member 25 form aligned circular bearings to fit about and embrace the peripheries of the central guideways in the wheels 23 and 24, journaling said gear wheels for axial rotation therein. The external periphery of said mounting member 25 extends outward beyond the periphery of the teeth on the gear wheels, for protective purposes.

Operation

When rotary power is applied to sheaves 18, the pinion shaft 19 is rotated, rotating pinion gear 20. The bull gear being in mesh with pinion gear 20 is thus rotated turning drive shaft 22. The drive shaft 22 rotates in the bearings in the stationary mountings 17 and turns the gear wheel 23, eccentrically affixed thereto. The gear wheel axially rotates in the upper portion of mounting 25, axially rotating the gear wheel 24 in the lower portion of mounting 25 and eccentrically turns the gear 24 on shaft 16. This converts the rotary motion of drive shaft 22 to rectilinear motion which is transmitted to reciprocable carriage 13 through shaft 16. Considering wheel 18 as being rotated in a clockwise direction, Fig. 3 shows the reciprocable carriage 13 at the top of the stroke, Fig. 1 shows the carriage 13 in partly lowered position, Fig. 4 shows the carriage at the bottom of the stroke and Fig. 2 shows the carriage in partially raised position.

It will be seen that 180° oscillation of the bull gear 24 will produce the same reaction on said reciprocable carriage 13.

By this improved construction disclosed herein the wear on the bearings journaling the shafts 22 and 16 is considerably reduced by providing two bearings in place of the previous one and by equally distributing the force of the thrust and pull over a larger bearing surface, enabling the use of much larger gear wheels, lengthening the stroke. The new gear wheel mounting or connecting member herein disclosed, provides many times greater bearing surface for the axial rotation of the gear wheels and is vertically aligned with the movable element to be driven. This also makes it practical to use larger gear wheels to lengthen the stroke. The same advantages which appear in the previous application, Serial Number 651,359 in giving progressive and smoothly operating upward and downward strokes, are present in this improved mechanism herein disclosed.

An alternative form of the gear wheel mount-

ing member, designated as 26, is provided, as shown in Figs. 6 and 7. This alternative form is of split two-piece construction and when assembled, completely encloses the peripheral portions of the gear wheels. The opposed sections have large, aligned gear wheel bearing apertures. It is necessary to provide a pair of gear wheels 27 and 28 which have the teeth of said gear wheels medially disposed about the periphery of said wheels. The marginal portions of the periphery of said wheels on either side of the teeth thereof, form guideways adapted to be sealingly embraced by the aligned bearing apertures of said casing 26 thereby enclosing the teeth of the gear within a chamber in which a lubricating fluid can be retained. This provides an additional safety feature of completely covering the teeth of the gear to prevent articles and objects from getting enmeshed therewith.

The operation of the alternative form is substantially the same as that of the form previously described, shaft 22 being fixed eccentrically within wheel 27 and shaft 16 being mounted eccentrically in wheel 28.

It will be seen that a highly efficient mechanism has been provided to convert rotary motion into reciprocating motion. Said mechanism is particularly adapted to carry large gear wheels which will permit a long stroke, desirable for pumping liquids such as oil and the like, from deep wells. The mechanism herein disclosed has the converting gears as well as the connecting and mounting means thereto aligned with the movable member to be driven. This feature gives the structure symmetry and evenly distributes the force of the downward thrust and upward pull on the bearings provided to take the same. In addition to these advantages, my improvement also embodies all of the advantages previously incorporated in my prior invention, Serial Number 651,359.

The laws of certain localities require that the teeth of the operating gears of machines such as pumps, to be used in homes and on farms, be protected from objects becoming enmeshed therein. Both forms of my gear wheel mountings provide the required protection under most of the existing laws. In addition to this, the alternative form provides a casing adapted to retain a lubricating fluid in which the gear wheels can rotate.

It will of course, be understood that various changes may be made in the form, details, arrangement and proportions of the parts without departing from the scope of my invention.

What is claimed is:

1. A reciprocable pump jack comprising a supporting structure, a drive shaft adapted to have rotary power applied thereto and journaled on said structure for rotation on a horizontal axis disposed in fixed relation to said structure, a rotary toothed gear wheel eccentrically fixed to said shaft for eccentric rotation about said fixed axis, a second toothed gear wheel of similar diameter to said first wheel and meshed therewith to be rotated thereby, a stub shaft eccentrically mounted in said second wheel to be reciprocated when said rotary wheels are rotated and adapted to apply reciprocating motion to a member to be reciprocated, said two gear wheels having aligned bearing races formed therein, a rigid gear wheel mounting member mounted around said races to journal the entire periphery thereof and positively hold said gear wheels in predetermined meshed relation.

2. A pump jack comprising a supporting structure, a drive shaft adapted to have rotary power applied thereto and journaled on said structure for rotation on a horizontal axis disposed in fixed relation to said structure, a rotary toothed gear wheel eccentrically fixed to said shaft for eccentric rotation about said fixed axis, a second toothed gear wheel of similar diameter to said first wheel and meshed therewith to be rotated thereby, a stub shaft eccentrically mounted in said second gear wheel to be reciprocated when said rotary wheels are rotated and adapted to apply reciprocating motion to a member to be reciprocated, said two gear wheels each having a pair of spaced rows of peripherally formed teeth with a central bearing race formed therebetween, a rigid gear wheel mounting member peripherally surrounding said races to journal said wheels and positively hold the same in predetermined meshed relation.

3. A pump jack comprising a supporting structure, a drive shaft adapted to have rotary power applied thereto and journaled on said structure for rotation on a horizontal axis disposed in fixed relation to said structure, a rotary toothed gear wheel eccentrically fixed to said shaft for

eccentric rotation about said fixed axis, a second toothed gear wheel of similar diameter to said first wheel and meshed therewith to be rotated thereby, a stub shaft eccentrically mounted in said second gear wheel to be reciprocated when said rotary wheels are rotated and adapted to apply reciprocating motion to a member to be reciprocated, said two gear wheels each having a pair of bearing races formed on both sides of the toothed portions thereof, and a rigid gear-enclosing member with a pair of bearings formed therein to receive the races of each wheel and completely enclose said wheels to hold the same in predetermined meshed relation.
